UNITED STATES PATENT OFFICE.

CARL E. BENSON, OF LAGUNA BEACH, CALIFORNIA.

DESIGN FOR A COMBINED AUTOMOBILE BODY, HOOD, AND RADIATOR.

Application filed March 9, 1927. Serial No. 21,069. Term of patent 14 years.

To all whom it may concern:

Be it known that I, CARL E. BENSON, a citizen of the United States, residing at Laguna Beach, in the county of Orange and State of California, have invented a new, original, and ornamental Design for Combined Automobile Body, Hood, and Radiator, of which the following is a specification, reference being had to the accompanying drawing, forming part thereof.

Figure 1 is a front elevation, and Fig. 2 is a plan view of a combined automobile body, hood and radiator showing my new design.

I claim:

The ornamental design for a combined automobile body, hood, and radiator as shown.

CARL E. BENSON.
